UNITED STATES PATENT OFFICE

LEE B. GREEN, OF LAKewood, OHIO, ASSIGNOR TO THE GLOBE MACHINE & STAMPING COMPANY, OF CLEVELAND, OHIO, A CORPORATION OF OHIO

DESIGN FOR A GRILLE FOR RADIATOR SHELL FRONTS

Application filed February 2, 1933. Serial No. 47,088. Term of patent 7 years.

To all whom it may concern:

Be it known that I, LEE B. GREEN, a citizen of the United States, residing at Lakewood, in the county of Cuyahoga and State of Ohio, have invented a new, original, and ornamental Design for a Grille for Radiator Shell Fronts, of which the following is a specification, reference being had to the accompanying drawing, forming part thereof.

In the drawing, Fig. 1 is a frontal perspective view of a grille for radiator shell fronts, showing my new design.

Fig. 2 is a section taken along the line 2—2 of Fig. 1.

I claim:

The ornamental design for a grille for radiator shell fronts, substantially as shown.

LEE B. GREEN.
